UNITED STATES PATENT OFFICE.

JOHN M. GRIEST, OF CHICAGO, ILLINOIS, ASSIGNOR, BY MESNE ASSIGNMENTS, TO THE CHICAGO ATTACHMENT COMPANY, OF SAME PLACE.

ART OF RIVETING METALS TOGETHER.

SPECIFICATION forming part of Letters Patent No. 290,229, dated December 18, 1883.

Application filed January 22, 1883. (No model.)

To all whom it may concern:

Be it known that I, JOHN M. GRIEST, of Chicago, in the county of Cook and State of Illinois, a citizen of the United States of America, have invented certain new and useful Improvements in the Art of Riveting Metals Together, of which the following, in connection with the accompanying drawings, is a specification.

10 In the drawings, Figure 1 is an edge view of a metallic piece upon which the first step in my process has been performed. Fig. 2 is a vertical central longitudinal section of the same. Fig. 3 is a like representation of two 15 parts riveted together by means of my improved process, showing in part the means employed for heading or spreading and completing the rivets. Fig. 4 is a vertical central longitudinal section of the two pieces riveted 20 together, and Fig. 5 is a top view of one of the riveted pieces.

Like letters of reference indicate like parts.

A represents a piece of comparatively soft metal, such as brass, and *aa* are studs punched 25 partly out therefrom by means of dies and punches, but not wholly removed therefrom, as shown. This is the first step relating to the formation of the rivets, and may be performed by means of any well-known or suitable dies 30 adapted for that purpose.

B in the example shown represents a piece 35 of metal—such as steel-plate—and *bb* are holes made therein. The position of the holes *bb* is such as to receive the studs *aa* when the piece B is laid against the piece A. The making of those corresponding holes in the piece to be riveted to the piece A may be regarded 40 as the second step in the method I follow, although it is not essential that these two steps should be taken in the order set forth. The next step is to lay the pieces A and B against each other in such manner that the studs *aa* will enter the holes *bb*, the said studs being long enough to extend slightly beyond the 45 plate B. The final step is to head the rivets down upon one piece and spread them laterally at their other ends in the other piece. This I accomplish by means of fixed studs *cc*, having conical ends adapted and arranged to

enter the sockets made by setting out the studs *aa*, in connection with vertically movable studs or headers *cc*, also having conical ends and arranged directly over the studs *cc*. To head the rivets, I lay the piece A on the studs *cc*, so that these studs will enter the sockets above referred to, having first placed the piece B on the piece A, so that the studs *aa* will enter the holes *bb*, the studs *cc* being raised sufficiently to permit both plates to be arranged between the studs *cc* and *cc*. To produce the best results, the conical parts of the studs *cc* should be in contact with the plate A when the points of those studs touch the inner ends of the studs *aa*. I then depress the studs or headers *cc*. By this means the upper ends of the studs *aa* will be spread out laterally or headed down upon the piece B by means of the studs *cc*, and their lower ends will also be spread out somewhat by means of the studs *cc*, which, as the piece A is thus pushed down upon them, will make the recesses in the piece A slightly flaring, while the points of the studs *cc* will enter the lower ends of the rivets and spread them out into these flaring recesses. The piece A will center itself on the conical points of the studs *cc*, so as to bring the upper ends of the rivets directly underneath the studs *cc*. I now raise the studs *cc* and remove the plates A and B, which will be very firmly riveted together.

It will be perceived from the foregoing description, and from reference to the drawings, that this method of riveting two parts together has many advantages. The work may be performed expeditiously and economically, and the parts are very strongly riveted to each other.

I am aware of the means employed by Jeremiah Carhart, as shown and described in Letters Patent of the United States No. 11,413, and granted to him August 1, 1854, for improvements in riveting metal plates, whereby he connects one plate to another by means of riveting; but I do not here intend to claim either the process or product described and shown in the said Letters Patent, my process and means being such as to head the rivets in the plate from which they are punched, as

herein shown and described, while the means employed by the said Carhart do not produce that result or the product of my process.

Having thus described my invention, what I claim as new, and desire to secure by Letters Patent, is—

An improvement in the art of attaching metallic plates or sheets to one another—to wit, preparing the plates by partially removing the metal from one of them, so as to produce on its surface a number of projecting studs, and by making holes corresponding thereto in

the other, superposing the plates one on the other, the studs on the one extending into and through the holes in the other, and then riveting the plates together by means of riveting-tools that shall simultaneously spread the metal and form heads on both the outer and the still-engaged inner end of each stud. 15

JOHN M. GRIEST.
